Application January 8, 1942, Serial No. 426,065

4 Claims. (Cl. 280—11.13)

This invention relates to improvements in laminated skis.

The main object of this invention is the provision of an improved method of manufacture whereby laminated skis of increased strength and "swing" retaining characteristics may be produced at a substantially reduced cost compared with present methods of manufacture.

Another object is the provision of a method of manufacture which enables the sides of a laminated ski to be shaped without resorting to the usual and undesirable practice of cutting away portions of the exposed side edges of the ski.

Another object is the provision of a method of manufacture whereby the "swing" desired in the finished ski is obtained in a simple and desirable manner without resorting to the steaming and heat bending operations usually employed for this purpose.

A further object is the provision of a generally improved laminated ski which is characterized by substantially increased strength, resiliency, wear resistance and "swing" retaining characteristics as compared with the various types of laminated skis now on the market.

A further object is the provision of a laminated ski composed of several layers, which are fabricated and assembled in a novel manner which reduces, to a considerable extent, the amount of wood wasted in the production of the ski.

Other objects, advantages and characteristic features of the invention will be more readily understood from the following detailed description taken in connection with the accompanying drawings, in which—

Fig. 1 is a side elevational view of a finished three-ply ski made in accordance with my invention.

Fig. 2 is a top plan view of the finished ski.

Fig. 3 is a bottom plan view of the finished ski.

Fig. 4 is an isometric view of the unfinished component layers and the unfinished toe and heel shaping and reinforcing wedges of the ski as these parts appear in unfinished condition and in an unassembled relation.

Fig. 5 is a top plan view of a built-up block or blank from which the top layer of the ski is cut.

Fig. 6 is a side view of the block or blank appearing in Fig. 5, the dotted lines in Fig. 6 indicating the manner in which the block or blank is cut longitudinally to provide top layers having a longitudinal curvature corresponding to the

longitudinal curvature or "swing" desired in the finished ski.

Fig. 7 is a side view of a second block or blank which is cut as indicated by dotted lines to provide intermediate ski layers having substantially the same longitudinal curvature as the top layers. The block or blank shown in Fig. 7 is built up in the same manner as that shown in Figs. 5 and 6.

Fig. 8 is a plan view illustrating a modified 10 method of forming the top and intermediate layers of the skis appearing in Figs. 1 to 3 inclusive.

Fig. 9 is a view showing the manner in which the front side shaping wedges of the top and intermediate layers appearing in Figs. 2, 4 and 8 15 may be cut from a short length of scrap board.

Fig. 10 is a view similar to Fig. 9 but showing the manner in which the rear side shaping wedges of the upper and lower ski layers may be cut from scrap board.

20 Referring to Figs. 1 to 3 inclusive, 5 designates a ski including a top layer 6, an intermediate layer 7, and a bottom layer 8 which are glued together in face to face relation except at the toe and heel ends of the ski. At the toe end of 25 the ski a toe shaping and reinforcing wedge 9 is interposed between and glued to the toe ends of the layers 6 and 7 and a similar wedge 10 is interposed between and glued to the toe ends of the layers 7 and 8. At the heel end of the ski a 30 similar heel shaping and reinforcing wedge 11 is interposed between and glued to the heel ends of the layers 6 and 7 and a similar wedge 12 is interposed between and glued to the heel ends of the layers 7 and 8.

35 As indicated in Fig. 4 the toe shaping wedges 9 and 10 are cut on the bias and are embodied in the toe portion of the ski so that the grain 9a of the wedge 9 extends diagonally across the width of the ski at an opposite inclination with 40 respect to the intersecting diagonally inclined grain 10a of the wedge 10. This method of crossing the diagonally inclined grains of the wedges 9 and 10 substantially increases the resistance of the toe portion of the ski to warpage, breakage 45 and splitting. The same effect is obtained at the heel end of the ski since the heel shaping wedges 11 and 12 are bias cut and are arranged so that the diagonally inclined grain 11a of the wedge 11 extends across the full width of the ski at an 50 opposite angle to the intersecting diagonally inclined grain 12a of the wedge 12.

Each of the layers 6 and 7 consists of a plurality of strips glued together in side by side relation. The two central longitudinally extending 55 strips 15 and 15a are substantially wedge shaped

strips arranged with their pointed ends directed toward but terminating in spaced relation to each other. These strips 15 and 15a extend inwardly from the toe and heel ends of the layer and have their side edges curved or shaped to correspond to the side curvature or side shape desired in the finished ski. The strips 15 and 15a are arranged between and glued to full length strips 16 which are also directly glued together along the portions thereof which lie between the pointed ends of the strips 15 and 15a. The remainder of the layer is composed of strips 17 and 18 which are glued to each other and to the strips 16. As viewed in plan the strips 16, 17 and 18 are of uniform width from the toe to the heel ends thereof. However, it will be noted that, due to the side shaping effect of the wedge shaped strips 15 and 15a, the layer as a whole gradually diminishes in width from the toe and heel ends toward the transverse centre of the layer, the maximum width being at the toe end since the butt end of the wedge shaped strip 15 is wider than the butt end of the wedge shaped strip 15a.

As shown in Figs. 9 and 10, the component strips 15 and 15a of each of the layers 6 and 7 may be cut from short lengths of board which are produced as waste in cutting long boards to provide the full length strips 16, 17 and 18.

After the wedge shaped strips 15 and 15a have been cut from a single board as shown in Figs. 9 and 10, the sides of these strips may, if necessary, be trimmed and shaped with very little waste to give the strips the side curvature or shape corresponding to the side curvature or shape desired in the finished ski.

The layers 6 and 7 of the ski may also be formed as shown in Fig. 8. In this case each layer includes two shaping wedges 15 extending from the toe end of the layer with their pointed ends directed toward the pointed ends of two shaping wedges 15a extending inwardly from the heel end of the layer. In this case the central portion of the layer is formed by three strips 22, 23 and 24 which are glued together, the outermost sides of the strips 22 and 24 being glued to the inner sides of the wedges 15 and 15a. The outer sides of the wedges 15 and 15a are glued to full length strips 25 which form the side edges of the layer.

It is preferable that the wedges 15 shown in Figs. 2, 4 and 8 be longer than the wedges 15a but this is not absolutely essential since the wedges may be of the same length.

The bottom layer 8 of the ski shown in Figs. 1 and 2 may, if desired, consist of a single piece of wood of a length and width corresponding to the length and width of the finished ski. I prefer, however, to employ a bottom layer 8 having a wide central strip 25, two intermediate strips 26, and two outer or edge forming strips 27. The central strip 25 is preferably formed with parallel side edges which are glued to straight side edges provided at the inner sides of the intermediate strips 26. The outer sides of the intermediate strips 26 are concavely curved to conform to the side shape or curvature of the overlying layers 6 and 7. The outer or edge forming strips 27 are of uniform width as viewed in plan and are pressed against and glued to the concavely curved outer side edges of the intermediate strips 26. The outer or edge forming strips 27 are preferably made of hickory or other hard woods, Balsam, metal or other material having a high wear resistance. The central strip 25 and the intermediate strips 26 may be made of relatively soft and

inexpensive wood. The intermediate strips 26 are provided since these strips are relatively narrow and may be cut to give the desired side curvature whereas it would not be feasible, with present methods of manufacture, to cut the side edges of a strip of the width of the central strip 24.

The layers 6 and 7 shown in Figs. 1 to 4 inclusive are cut from built-up blanks or blocks of the type shown in Figs. 5 to 7 inclusive, said layers 10 being formed by cutting the blocks or blanks longitudinally along curved lines represented by the dotted lines X, each layer being thus given a bottom longitudinal curvature or "swing" corresponding to that desired in the finished ski. This 15 method of cutting the layers 6 and 7 eliminates the necessity of steaming and heat bending operations which are originally resorted to in bending the component layers of a ski to give the latter the required "swing."

In making up a ski in accordance with the present invention the curved layer 6 is superimposed on the curved layer 7 and the bottom layer 8 is then applied to the lower surface of the layer 7, the resulting assembly being then subjected to a molding operation in which the component layers are united by adhesive previously applied thereto, the bottom layer 8 being bent to conform to the curvature of the engaging surface of the intermediate layer 7 and the toe ends 25 of all of said layers being curved upwardly in the conventional manner. In this case the molding operation required to bend the toe ends of the layers and to cause the bottom layer to conform to the longitudinal curvature or "swing" of the superposed layers 6 and 7 is a relatively simple and inexpensive operation as compared with the steaming and heat bending operations required when the layers 6, 7 and 8 are initially combined as flat layers and must all be bent simultaneously to give the desired "swing" or longitudinal curvature.

When the layers 6 and 7 are made as shown in Fig. 8 they will also be cut from suitable built-up laminated blocks or blanks of the same general type as those shown in Figs. 5 to 7 inclusive.

Having thus described the principles of my invention and what I now conceive to be the preferred embodiment thereof, it will be understood that various modifications may be resorted to within the scope and spirit of the invention as defined by the appended claims. For example, while I have shown my invention embodied in a three layer ski, it will be understood that the same principles apply to the construction of all multi-layer skis composed of two or more layers.

Having thus described my invention, what I claim is:

1. A multi-layer laminated ski characterized in that at least one layer is composed of separately formed strips glued together in side by side relation, certain intermediate strips being substantially wedge shape in plan view and being arranged in line with each other and with their pointed ends directed toward but terminating short of the transverse centre of the layer, said wedge shaped strips being arranged between and glued to two full length strips which are also glued directly to each other along the portions thereof lying between the pointed ends of the wedge shaped strips, the side shape or curvature of the layer being determined by the side shape or curvature of the wedge shaped strips.

2. A multi-layer ski as set forth in claim 1, in which the strips of the layer containing the wedge shaped strips are, with the exception of

the wedge shaped strips, of uniform width as viewed in plan.

3. A multi-layer ski comprising at least three superposed layers, toe shaping wedges interposed between the toe and heel ends of the top and intermediate layers and similar toe shaping wedges interposed between the toe and heel ends of the intermediate layer and the bottom layer, said wedges comprising pieces of wood which are cut on the bias and arranged between the layers so that the obliquely inclined grains of the upper toe and heel shaping wedges extend across the full width of the ski at an opposite angle with respect to the obliquely inclined grains of the lower toe and heel shaping wedges.

4. A multi-layer laminated ski comprising a layer including two centrally arranged wedge-shaped strips extending inwardly from the toe and heel ends of the layer in alignment with each other, said wedge-shaped strips being arranged with their pointed ends directed toward each other but terminating short of the transverse

5 portions thereof lying between the pointed ends of the wedge shaped strips and further strips arranged outwardly of said additional strips, another layer of said ski, which constitutes the bottom layer or sliding surface, being composed 10 of a relatively wide full length central strip having parallel side edges, relatively narrow intermediate strips having straight inner side edges glued to the side edges of the central strip, the outer side edges of the intermediate strips being 15 concavely curved, and outer or edge forming strips secured to and extending the full length of the outer concavely curved side edges of the intermediate strips, said outer or edge forming strips being of uniform length from end to end 20 as viewed in plan.
